HOLLOW METALLIC CONSTRUCTION PILLAR

Akemasa Otani, 23-14, 204, Takanawa 3-chome, Minato-ku, and Kenichi Watanabe, 23-19, Kamiikedai 4-chome, Ota-ku, both of Tokyo, Japan

Filed Apr. 27, 1972, Ser. No. 248,353

Claims priority, application Japan Oct. 30, 1971

Term of patent 14 years

Int. Cl. D25—01

U.S. Cl. D13—1 H

FIG. 1

FIG. 2

FIG. 3

FIG. 1 is an elevational view of a hollow metallic construction pillar showing our design;

FIG. 2 is a top plan view thereof, and

FIG. 3 is a cross-section of the pillar taken along the section line A—A' shown in FIG. 1.

We claim:

The ornamental design for a hollow metallic construction pillar, as shown.
